UNITED STATES PATENT OFFICE.

ALFRED SMITH, OF WOODWORTH, INGROW, KEIGHLEY, ENGLAND.

DRIVING BAND OR TAPE.

1,187,558.

Specification of Letters Patent. Patented June 20, 1916.

Application filed January 30, 1914. Serial No. 815,448.

To all whom it may concern:

Be it known that I, ALFRED SMITH, a subject of the King of Great Britain, and residing at Woodworth, Ingrow, Keighley, in the county of York, England, have invented certain new and useful Improvements in Driving Bands or Tapes, of which the following description, together with the annexed sheet of drawings, is a specification.

10 In the production of driving belts or bands for varied purposes, but especially of the class known as driving tapes for spinning, twisting and like machines used in the production of yarns or threads of fibrous substances, it is desirable that while maintaining the strength of said tapes their flexibility shall not be interfered with since it is essential that the same shall be sufficiently flexible to conform to the contours or peripheries 15 of the driving pulleys or whirls (which are of comparatively small diameter) to which they have to transmit motion.

My invention consists in constructing these belts and tapes and carrying out the method 25 of jointing the same together as hereinafter described so as to secure the desired strength and flexibility.

In the accompanying sheet of drawings:— Figure 1 is a perspective view illustrating 30 the formation of a belt or tape constructed or woven in accordance with my invention. Fig. 2 represents the two ends of tape cut or shaped so that they may be jointed together as hereinafter described. Fig. 3 is a plan of 35 a similar formation of joint to that shown by Fig. 2. Fig. 4 is a perspective view showing a small driving pulley on a spindle with a tape partly encircling the same. Fig. 5 is a perspective view illustrating a modification 40 in the construction of my improved driving belt or tape.

In accordance with my invention instead of producing a tape or belt of sufficient thickness to withstand the whole strain in a single 45 strand, I produce the tape in two parts *a*, *a'* and *b*, *b'*, one part as *a*, *a'* being superposed or laid over the other part *b*, *b'* the two being secured together somewhat in a central position *c* between their outer edges and 50 throughout their whole lengths. This securing together of the two tapes *a*, *a'* and *b*, *b'* is preferably effected by the process of weaving in which the two sides *a*, *b* and *a'*, *b'* are produced separately, while by the 55 weft catching the warp threads at the part *c* about midway between the two edges the

two separate fabrics are secured to each other in this part.

Any form or order of treading in the loom may be followed to attain the object desired 60 and one shuttle alone may be employed or two or more shuttles may be made use of as is well known to those having knowledge of this process of weaving.

It is obvious that the two tapes or belts 65 which are bound together may be produced separately and afterward stitched or sewn together longitudinally at the part *c* approximately midway between their two edges.

In the production of belts in accordance 70 with my invention the edges *a*, *a'* and *b*, *b'* may be of considerable thickness as shown by Fig. 5, while the central part *c* may be of less thickness and comparatively flexible whereby strength is given and yet the flexi- 75 bility of the whole is retained.

When jointing together the two ends of the tapes or belts produced in accordance with my invention so as to form them endless for the purpose of transmitting motion to 80 the parts they have to drive, as to the small driving pulley *d* upon the spindle *e*, the parts *a* and *a'* on one (say the upper) side of the belt are cut away somewhat as shown by Figs. 2 and 3 while the parts *b* and *b'* 85 (say on the underside) are retained. On the other hand the parts *b* and *b'* are cut away at the other end of the tape so as to form them to fit over the parts retained at *a*, *a'* on the other ends *b*, *b'* of the tape to produce a 90 jointing to correspond in thickness to the two parts forming the body of the tape, while to secure the greatest strength at this jointing, one part is made longer than another that is to say, the part *a'* is cut short 95 while the part *a* extends beyond said shorter part and the part *b* extends beyond the part *b'*, so that in being jointed together as shown by Fig. 3, the cut parts *f*, *f'*, *f''*, *f'''*, of the tape do not lie opposite each other, but occupy 100 different positions in the length thereof, thus producing at every part of the joint approximately three quarters the strength of that of the body part of the tape.

Such being the object of my invention;— 105 what I claim is:—

1. A driving belt formed of superposed members woven together along a longitudinal line intermediate of their edges, said edges being free. 110

2. A driving belt formed of superposed members united intermediate of their longi- 115

tudinal edges, said edges being free, the middle portion of the completed belt being of less thickness than the edge portions.

3. A driving belt formed of superposed members woven together along a longitudinal line intermediate of their edges, said edges being free, the middle portion of the completed belt being of less thickness than the edge portions.

10 4. A driving belt formed of superposed members united intermediate of their longitudinal edges, said edges being free, the ends of the members of said belt being cut away to provide complemental portions shaped to 15 overlap to form a joint approximately the same thickness as the body of the belt.

5. A driving belt formed of superposed members united intermediate of their longitudinal edges, said edges being free, the ends of the members of said belt being each cut away at one side to provide complemental portions shaped to overlap to form a joint approximately the same thickness as the body of the belt.

20 In testimony whereof I have signed my name to this specification in the presence of two witnesses.

ALFRED SMITH.
